(57) **CLAIM**

The ornamental design for a purifier for use in grain milling installations, as shown and described.

DESCRIPTION

1. Purifier, for use in grain milling installations

1.1 : Perspective

1.2 : Left

1.3 : Right

1.4 : Front

1.5 : Back

1.6 : Top

1.7 : Bottom and

1.8 : Perspective.

The parts shown by means of blue coloring in the reproductions are not part of the claimed designs.
